UNITED STATES PATENT OFFICE.

NICOLAS HERZMARK, OF PARIS, FRANCE.

APPARATUS FOR STARTING EXPLOSION-ENGINES.

1,217,762.

Specification of Letters Patent. Patented Feb. 27, 1917.

Application filed July 28, 1914. Serial No. 853,732.

To all whom it may concern:

Be it known that I, NICOLAS HERZMARK, a subject of the Emperor of Russia, and a resident of 16 Rue José Maria de Heredia, 5 at Paris, France, have invented new and useful Improvements in Apparatus for Starting Explosion-Engines, of which the following is a specification.

The present invention relates to an apparatus for starting explosion engines and more particularly the engines of automobile vehicles.

The accompanying drawings represent by way of example a form of construction of 15 the subject of the invention:

Figure 1 is an elevation of the apparatus, in part section.

Fig. 2 is a corresponding plan.

Fig. 3 is an elevation of the operating 20 handle.

Fig. 4 is a view from the right of Fig. 3.

The remaining figures are drawn on a larger scale:

Figs. 5, 6 and 7 are details.

25 Fig. 8 is a section on line 8—8 of Fig. 5, seen from the left.

Figs. 9 to 11 show an arrangement which allows of locking the operating handle and the controlling cable in the position of rest.

30 Fig. 9 is an elevation of the device.

Fig. 10 is a corresponding plan.

Fig. 11 is a section on line 11—11 of Fig. 9, seen from the left.

35 Figs. 12 and 13 show a modification of the means for guiding the controlling cable.

Fig. 12 is a side elevation in part section.

Fig. 13 is a section on line 13—13 of Fig. 12.

40 The apparatus comprises essentially a ratchet wheel A fixed upon the engine flywheel, a stationary crown B fixed to the frame or chassis, and a movable operating pawl C guided inside the crown B and controlled in both directions by means of a flexible cable D.

45 The ratchet wheel A is secured to the flywheel E by means of knee-pieces a fixed by screws (see especially Fig. 2). These knees are suitably offset so as to carry the ratchet wheel A clear of the flywheel E and to permit the movement of the clutch cone F. The knees a may be made extensible by means of slides so as to allow of fixing the ratchet wheel A upon a flywheel of any diameter; 50 they may also have marks and graduations to facilitate fitting and to insure perfect cen-

tering of the ratchet wheel upon the flywheel.

The guiding crown B (Figs. 1 and 2) which surrounds the ratchet wheel A is secured to the chassis G of the vehicle by means of bolted brackets b which may also be extensible. The crown B has a trough- or U-section (see especially Fig. 8) and at one side an opening b¹ through which the controlling cable D enters inside the crown B. The side webs or flanges of the crown B are provided upon a part of their peripheries with an external circular rib b² which serves to guide the driving pawl C. The ribs b² at one end have an incline or ramp b³ which goes away from the ratchet wheel A along a tangent to the circumference of the ribs b².

The driving pawl C is mounted at the end 75 of the operating cable D. It consists (see especially Fig. 5) of a member c provided with lateral guiding hooks c¹ which slide along the ribs b² on the crown B. The pawl C comprises also a roller c² by means of 80 which it rolls in the trough of the crown B, a tooth c³ which forms the pawl itself and is pivoted around an axis c⁴, and a union c⁵ hinged at c⁶ to which is attached the end of the cable D. The tooth c³ can withdraw 85 from operation by turning in the direction of the arrow x around the axis c⁴ (Fig. 5); while by turning in the direction opposite to the arrow x it brings its nose c⁷ against a stop c⁸ upon the member c. A spring 90 plunger catch c⁹ which then enters a corresponding nick in the member c holds the tooth c³ in its raised position. The tooth c³ is also provided with a second nose c¹⁰ which sets up the tooth c³ again when it meets a 95 stop h arranged at one end of the ribs b², in front of the ramps b³ (Fig. 6).

The cable D consists preferably of a core d and a helical casing d¹ (see especially Figs. 5 and 7); it is guided between the opening 100 b¹ and the operating handle J by a rigid sheath d².

Fig. 7 shows in axial section the method of connecting the cable D to the operating handle J. The core d is attached at the end 105 of a tube i screwed at one end into a nut i¹ and a socket i² (see also Fig. 3) and at the other end into a cone i³ against which there abuts the helical casing d¹. The cone i³ fits into an outer cone i⁴ secured to the sheath 110 d². The tube i can be fixed to the nut i¹ by means of a locking screw i⁵. By turning

the nut i^1 the tube can be brought toward or moved away from the cone i^4 , thereby altering the tension of the cord d .

The handle J is hinged to the socket i^2 so that it can be turned down upon the floor-board of the vehicle (see especially Fig. 4) in order not to incommod the driver in operating the accelerator and brake pedals. It can however be connected to the socket i^2 by a readily detachable fitting; in this case it is easy to remove the handle J so as to prevent the starting of the engine and therefore the theft of the vehicle.

The working of the apparatus is as follows: In the position of rest, the handle J is pushed down to the end of its stroke and the driving pawl C occupies the position I shown in full lines in Fig. 6. The ramp b^3 upon the guide ribs b^2 then separates the pawl C sufficiently far from the ratchet wheel A for the tooth c^3 to be quite incapable of engaging with the teeth of the ratchet wheel. The tooth c^3 is also raised because the nose c^{10} is in contact with the stop h . In order to start the engine, the handle J is taken and pulled, gently at first. The pawl C moves in the direction of the arrow y (Fig. 6), rising along the ramp b^3 so as to approach the ratchet wheel A . The tooth c^3 comes into engagement with the teeth of the ratchet wheel, which is thereby set in rotation (position II shown in heavy dotted lines in Fig. 6). It is then sufficient to give a sudden pull upon the handle J to revolve the wheel A and therefore the fly-wheel E , that is to say to start the engine. In this movement, the cable D bears upon the periphery of the ratchet wheel A in the manner of a belt (see position of this cable D shown in Fig. 1).

As soon as the engine starts, the ratchet wheel A knocks down the tooth c^3 into its inactive position. The driving pawl is then pushed back into its position of rest by returning the cable D into its sheath by means of the handle J . The position III represented in chain lines in Fig. 6 shows the pawl C during its backward movement. In this return stroke the part of the cable D contained in the crown B rests in the bottom of the trough, which reduces to a minimum the wear of the cable.

It may be pointed out that the apparatus of the present invention protects from the disadvantages which usually occur in back-fires of the engine. For on the most unfavorable supposition, the pawl C is simply driven back by the ratchet wheel A in a direction opposite to the arrow y as far as b^3 where the tooth c^3 is automatically released. But more often the starting movement imparts to the ratchet wheel A a quicker movement than is retained by the pawl C toward the end of its stroke; consequently the pawl c^3 is driven down out of

the way before the back-fire has had time to take place, so that the backfire does not even effect the return of the operating handle J .

There may be a disadvantage in leaving the handle free as shown in Fig. 4 in the position of rest of the apparatus, because under the influence of the vibrations of the vehicle the handle tends to jump up and to draw the cable D against the periphery of the ratchet wheel A ; this involves rapid wear of the cable.

In order to overcome this drawback there may be employed the device shown in Figs. 9 to 11. This device consists in a pincer K pivoted at a point k^1 upon the floor-board of the vehicle. Two arms k^2 of the pincer are turned up at right angles and are subjected to the action of a spring k^3 which tends to bring them together; these arms are arranged in such a way that the stem of the handle J can be engaged between them. The two other arms k^4 which open when the arms k^2 close together, are arranged in such a way as to encircle a groove or neck formed in the periphery of the socket i^2 .

In the position of rest, the apparatus has the handle J engaged between the arms k^2 of the pincer, these arms being thereby separated; the arms k^4 are therefore brought together so as to clamp the socket i^2 and the cable D . In order to start the engine, the handle J is taken and released from the pincer arms k^2 ; the spring k^3 therefore separates the arms k^4 and so liberates the socket i^2 and thereby the cable D .

It is moreover quite evident that the invention is not limited to the details of construction which have been described, but that it can be carried out with any desired modifications based upon the same principle. Thus for example in certain cases the sheath d^2 which guides the cable between the opening b^1 and the operating handle J may be replaced by the guiding means shown in Figs. 12 and 13. This device consists of a half-sheath m mounted outside the curve of the cable D and rollers m^1 mounted inside the curve of the cable and journaled in the walls of the half-sheath m . A series of holes m^2 drilled beforehand in the walls of the half-sheath m allows of mounting the rollers m^1 at the desired position. When a pull is exerted upon the cable D , it bears upon the rollers m^1 , which reduces friction to the minimum, whereas when it is pushed down to return the pawl C to the position of rest, it comes to bear in the bottom of the half sheath m .

On the other hand the cable D might be of a type other than that described. This cable must however be of relatively large diameter, in order not to be deformed when subjected to compression. If a solid cable of large diameter were employed, this cable

would be wanting in flexibility. On the other hand the cable hereinbefore described presents the advantage of having a large diameter while yet remaining sufficiently flexible.

5 Lastly the pawl C and the ratchet tooth-
ing upon the wheel A could be replaced by
other running escape devices of known type,
such as friction-releases, friction-ratchets, etc.

10 What I claim and desire to secure by Letters Patent of the United States is:

15 1. A starting device for explosion engines, comprising a ratchet wheel operatively connected to the engine shaft, a stationary guide around the same, a flexible cable manually movable in opposite directions, a hand grip connected to the outer end of said cable for operating the same in both directions in said guide, a carrier attached to the 20 free inner end of said cable, a pawl pivoted to said carrier for engaging the ratchet wheel on the movement of said cable in one direction, and means engaging said pawl at substantially the end of its non-working 25 travel for setting it up in position to engage the ratchet on the driving movement of the cable.

30 2. A starting device for explosion engines, comprising a ratchet wheel operatively connected to the engine shaft, a stationary guide around the same, a pivoted pawl having a one-way engagement with said ratchet, a carrier for the pawl moving on the guide, said guide having a deflected reach at one 35 end to hold the pawl out of engagement with the ratchet wheel, and means engaging the pawl during its travel in said deflected reach for setting it up into position to engage the ratchet wheel on the driving movement of 40 the cable.

35 3. In a starting device for explosion engines, a ratchet wheel fast with the engine shaft, a stationary member around the same, guide ribs on said stationary member, and a 45 pawl sliding on said ribs and adapted to engage the ratchet wheel, together with means for moving said pawl while in engagement with said ratchet wheel, and means operative upon the return movement of said pawl

50 for properly positioning the same to again engage the ratchet wheel on the driving movement thereof in the opposite direction.

4. In a starting device for explosion engines, a ratchet wheel fast with the engine shaft, a stationary member around the same, 55 guide ribs on said stationary member, and a pawl sliding on said ribs and adapted to engage the ratchet wheel, together with means for moving said pawl while in engagement with said ratchet wheel, and means operative upon the return movement of said pawl for properly positioning the same to again engage the ratchet wheel on the driving movement thereof in the opposite direction, and a detent for holding the pawl in this 65 position.

5. In a starting device for explosion engines, a ratchet wheel operatively connected to the engine shaft, a pawl having a one-way engagement with said ratchet wheel, a cable 70 for operating the pawl, a handle at one end of the cable, and a latch for holding said cable and handle, said latch comprising a pair of double arm levers, a spring between said levers at one end tending to hold said ends together and the other ends apart, said parted ends embracing the cable and gripping the same when the spring-engaged ends are spread by the insertion therebetween of 75 the handle.

6. In a starting device for explosion engines, a fly-wheel a clutch engaging the fly-wheel, a ratchet wheel, brackets rigidly spacing the latter from the fly-wheel a sufficient distance to permit the operation of 85 the clutch and a pawl device for temporarily engaging the ratchet wheel to rotate the same, together with a guide surrounding the fly-wheel and supported from the chassis and means for mounting the pawl device 90 therein.

In testimony whereof I have signed my name to this specification, in the presence of two subscribing witnesses.

NICOLAS HERZMARK.
